UNITED STATES PATENT OFFICE.

MARION R. CASEY, OF CLINTON, SOUTH CAROLINA, ASSIGNOR, BY DIRECT AND MESNE ASSIGNMENTS, TO CLINTON CAM COMPANY, OF CLINTON, SOUTH CAROLINA, A CORPORATION OF SOUTH CAROLINA.

CAM.

1,177,304.

Specification of Letters Patent. Patented Mar. 28, 1916.

Application filed October 1, 1915. Serial No. 53,613.

To all whom it may concern:

Be it known that I, MARION R. CASEY, a citizen of the United States of America, and a resident of Clinton, county of Laurens, 5 State of South Carolina, have invented certain new and useful Improvements in Cams, of which the following is a full and clear specification.

Before my invention, it was the common practice to junk worn cams and replace them by new ones, except that in certain instances cams have been provided with detachable and renewable faces and points.

It is the object of the present invention 15 to provide simple means for patching those portions of the periphery of a cam which it is not feasible to make detachable, and thus greatly prolong the life of the cam, as more fully hereinafter set forth.

20 In the drawings Figure 1 is an elevation of one side of a loom cam showing my patch applied thereto; Fig. 2 is a similar view of the opposite side of the cam; Fig. 3 is a sectional view on the line 3—3 of Fig. 25 1; and Fig. 4 is a detail perspective view of the cam patch.

In the drawings, I have illustrated my 30 device as applied to a well known type of loom cam in which the point *a* is made detachable from the main part of the cam, this point being clamped to the main cam by means of a bolt *b* and being fitted into a peripheral notch formed in the cam coincident with the point thereof. In this type of 35 cam, the periphery just back of the point *a* soon becomes so worn, as designated by the letter *c* in Fig. 1, that a new cam has to be provided, thus entailing not only the delay of replacing the cam with a new one, but 40 also the loss of a cam.

To bridge or carry the roll or ball that usually works on the cam periphery across the worn part *c*, I affix to one side of the cam a plate *d* whose peripheral surface *e* 45 conforms to the curvature of the cam face at that point, so that the roll or ball runs on the surface *e* as it passes over the worn part. On the inner face of the patch plate *d*, along the peripheral edge thereof, I form 50 a groove *f* which engages under the usual lateral flange *g* of the cam and thus assists in alining the peripheral surface *e* of the patch with the peripheral surface of the cam. One end of the patch plate is fastened 55 against the cam body by the same bolt *b*

which fastens the detachable point *a* to the cam, and the other end of the patch plate is bolted removably in position by means of an extra bolt *h* which is passed through a slot *i* in the patch and the usual arcuate slot *l* 60 formed in the cam at a point back of the point. The two slots *i* and *l* permit of the adjustment necessary to bring the peripheral or operative surface *e* of the patch into nice alinement with the periphery of the 65 cam proper.

It will be understood that while I illustrate my patch as applied to a loom cam, I may so proportion and shape the patch that it may be used on a great variety of cams 70 and tappets; and I therefore do not wish to be limited to a loom cam in the application of my invention.

It will be observed that when the patch is applied to the cam in the position illustrated, namely, just behind the point of the cam, or, in other words, at the point of largest diameter of the cam, the patch serves to overweight the cam at that point. I have found in practice that if this type of cam, 75 thus overweighted, is used in a certain type of loom, I obtain very important advantages in the running of the loom. I do not claim this broad idea in this application, as the same is made the subject matter of a co- 80 pending application Serial No. 74,793, filed 85 January 28, 1916.

Having thus described my invention, what I claim is:

1. The combination with a cam having a 90 portion of its periphery worn down, of a patch plate bolted to the side of the cam at a point coincident with said worn portion and having an operative or peripheral surface bridging said worn portion in circumferential alinement with the peripheral surface 95 of the cam.

2. The combination with a cam having a portion of its peripheral surface worn down, 100 said cam being provided with a lateral flange *f* at its periphery, of a patch and means for bolting it at the side of the cam at a point coincident with the worn down portion, the peripheral surface of this patch bridging the worn down portion and lying 105 in alinement with the peripheral surface of the cam, said patch plate being provided with a groove or rabbet *f* along its inner peripheral edge to engage under said lateral flange.

3. The combination with a loom cam having a detachable point, and a bolt for fastening this point to the cam, of a patch plate having its forward end fastened to
5 the cam by the aforesaid bolt, a bolt for fastening the other end of the cam plate to the cam, said patch plate having its pe-

riphery in circumferential alinement with the periphery of the cam proper, for the purpose set forth.

In testimony whereof I hereunto affix my signature.

MARION R. CASEY.
